THE STAY

Everett W. Sharkey, Woodhaven, N. Y.

Application September 15, 1936, Serial No. 100,813

4 Claims. (Cl. 24—49)

This invention relates generally to improvements in tie stays, and more particularly to an adjustable tie stay which is applied externally to the knot of a four-in-hand tie, whereby twisting and displacement of the knot about a collar are eliminated.

The main object of the invention resides in the provision of a device of the type above mentioned wherein external adjustable finger means adapted to set at the base of the lateral edges of a knot are employed in conjunction with a prong member adapted to penetrate the under depending portion of the tie, thereby preventing vertical and lateral displacement of the tie knot relative to the depending portions of the tie.

A still further object of the invention is to provide a device of the above type which is simply applied to the tie after the formation of a knot, without affecting the condition of the latter, the said device being durable and economical to manufacture.

These objects and other incidental ends and advantages of the invention will hereinafter appear in the progress of the disclosure and as pointed out in the appended claims.

Accompanying this specification is a drawing showing a preferred form of the invention and wherein corresponding reference characters designate corresponding parts throughout the several views.

In accordance with the drawing:

Figure 1 is a view in perspective of the improved tie stay.

Figure 2 is a front view in elevation of the tie stay as applied to a four-in-hand tie, showing a slight constriction caused thereby at the lower portion of the tie knot.

Figure 3 is a side view in elevation of the tie stay as shown in Figure 2.

Figure 4 is a fragmentary view in elevation partly in section, showing an alternate securing means for the lower ends of the arm members of the tie stay, together with a prong secured thereto.

In accordance with the invention and in accordance with a preferred form thereof shown in the accompanying drawing, numeral 10 indicates a tie knot of a four-in-hand tie having a front depending portion 11 and a rear depending portion 12. Numerals 13 and 14 indicate two diverging and resilient arm members, the upper end portions 15 and 16 thereof being respectively angularly offset, preferably at approximately ninety degrees. The said end portions 15 and 16 form forwardly projecting lateral guides within which the base or lower portion of the knot 10 is main-

tained under slight pressure, thereby causing a constriction at the base of the tie knot 10 to present a neater appearance. The lower ends of the said arm members 13 and 14 are secured together in any suitable fashion whereby a prong or pin 22 is made to depend therefrom. One form of such junction of the lower ends of arms 13 and 14 is shown in Figure 1 wherein a receiving member 17 is provided with two adjacent and vertical tubular members 17' and 18 into which the lower ends of arms 13 and 14 are secured by any suitable means such as brazing or soldering. From the lower end of receiving member 17 the depending prong or pin 22 is secured to run co-axially with the long axis of the 15 device.

In order to adjust the distance between the forwardly projecting lateral guides 15 and 16, a bar member 19 is provided which is adapted to slide along arm members 13 and 14 through orifices 20 and 21. By raising the bar member 19 the distance between lateral guides 15 and 16 is reduced while by lowering the said bar member, the distance is increased. The convergence of arms 13 and 14 at the lower portions effectuates a lower stop for the said bar member 19 while the forwardly projecting lateral guides 15 and 16 serve as the upper stop for the said bar member 19.

Figure 4 shows a method of eliminating the mounting of arm members 13 and 14. This is accomplished by utilizing a single resilient wire for the formation of the tie stay, the wire being bent or looped as at 23, into a substantially U-formation with the arm members 13 and 14 diverging upwardly from the said bend. After such bending operation, bar member 19 is inserted through the upper ends of the said arms by means of orifices 20 and 21. Thereupon the upper end portions of arm members 13 and 14 are angularly offset to form the forwardly projecting guides 15 and 16. Pin or prong 22 is suitably secured to the lower end of bend 23.

In practice, lateral guides 15 and 16 are preferably positioned at the lower portions of the sides of tie knot 10 for purposes of adjustment, although they may be positioned directly below if desired. When the guides 15 and 16 have been adjusted to a gripping position of the knot by raising or lowering bar member 19, the prong 22 is forced into the rear depending portion 12 of the tie, at which time the device is firmly secured in place. The prong 22 secures the knot 10 against slipping vertically along the rear depending portion 12 of the tie while lateral 55

guides 15 and 16 prevent knot 10 from being laterally displaced therealong while within a collar. To remove the device from the tie, the lateral guides 15 and 16 are removed from the knot 10 by either lowering bar member 19 or forcing lateral guides 15 and 16 rearwardly from the knot. When the said guides 15 and 16 are free of knot 10, prong 22 is withdrawn from the rear depending portion 12 of the tie. Pin or prong member 22 may be outwardly offset relative to the longitudinal axis of the device, if desirable, whereby the arm members 13 and 14 would make a closer contact with the rear depending portion 12 of the tie.

15 I wish it understood that minor changes and variations in the integration, substitution and relative positions of the parts, may be resorted to without departing from the spirit of the invention and without departing from the appended claims.

20 The forwardly projecting lateral guides 15 and 16 are provided with rough inner edges 24 and 25 in order to offer friction to the tie knot 10, as shown in Figure 1. Any other means, however, may be employed for such purposes.

I claim:

1. A tie stay for a four-in-hand tie comprising resilient and diverging arm members, the upper end portions of said arm members both being angularly offset to serve as forwardly projecting and adjustable external lateral guides for the knot, a bar member slidable along the said arm members thereby adjusting the distance between the said guides, the lower end portions of the

said arm members being joined together, and a securing prong depending from the junction of the lower ends.

2. A tie stay for a four-in-hand tie comprising resilient and diverging arm members formed 5 from a single piece of wire and extending upwardly from the lower loop portion, the upper end portions of said arm members both being angularly offset to serve as forwardly projecting and adjustable external lateral guides for the 10 knot, a bar member slidable along the said arm members thereby adjusting the distance between the said guides, and a securing prong depending from the lower loop portion and adapted to penetrate the under depending portion 15 of the tie.

3. A tie stay for a four-in-hand tie comprising two forwardly projecting and external lateral guides for the knot, resilient and diverging upright arm members from which the said guides 20 project, the said arm members at the lower end being joined together, and a securing prong depending from the said junction.

4. A tie stay for a four-in-hand tie comprising two forwardly projecting and adjustable external lateral guides for the knot, resilient and divergent upright arm members from which the said guides project, a bar member slidable along the said arm members thereby adjusting the distance between the said guides, the said arm 30 members at the lower end being joined together, and a securing prong depending from the said junction.

EVERETT W. SHARKEY.
